UNITED STATES PATENT OFFICE.

EDWIN M. CLARK, OF CLARKSTON, MICHIGAN.

TIME-CONTROLLED LOCKING MECHANISM.

Application filed July 23, 1921. Serial No. 486,962.

To all whom it may concern:

Be it known that I, EDWIN M. CLARK, a citizen of the United States, residing at Clarkston, in the county of Oakland and 5 State of Michigan, have invented a new and useful Time-Controlled Locking Mechanism, of which the following is a specification.

This invention relates to time controlled locking mechanisms, and particularly relates 10 to time controlled drawer locks.

It is the object of the invention to safeguard cash drawers, or other receptacles for valuables, against robbery (and especially hold-up) by providing means controlled by 15 a conveniently located electric switch or switches for automatically effecting closing and locking of such drawers or receptacles.

A further feature of the invention is the provision of mechanism, energized as the 20 drawer is closed and locked, for effecting unlocking after a predetermined lapse of time sufficient to insure safety after an attempted robbery or hold-up which has necessitated operation of the automatic locking means.

25 In attaining these objects the invention contemplates associating with a cash drawer, or other receptacle for valuables, an electric motor adapted, by means of suitably disposed switches to be energized, immediately 30 upon discovery of the presence of a hold-up man, said motor driving mechanism, for first effecting closing and locking of the drawer or receptacle and thereupon energizing a slow motion drive for releasing the 35 lock after a predetermined interval.

A preferred embodiment of the invention is hereinafter described and is illustrated in the accompanying drawings, wherein,

Fig. 1 is a plan view of the invention as 40 applied to a cash drawer, the latter being shown in closed position.

Figs. 2, 3 and 4 are views taken upon a common line 2—2, 3—3 and 4—4 of Fig. 1, showing the drawer in section and the associated mechanism in elevation, and in different positions of adjustment.

Fig. 5 is a vertical section on line 5—5 of Fig. 1, showing the driving parts carried by a certain shaft.

50 Fig. 6 is a sectional detail taken on line 6—6 of Fig. 1.

Fig. 7 is a sectional detail of a ratchet wheel and pawl, taken on line 7—7 of Fig. 1.

Fig. 8 is a sectional detail on line 8—8 of Fig. 1.

In these views the reference character 1 designates a cash drawer having the parallel rearward extensions 1' respectively at each side thereof. Between said extensions 60 there is arranged a stationary base or platform 2 upon which is mounted actuating and locking and unlocking mechanism for the drawer. Upon the platform 2, substantially midway between the ends thereof, a rock-shaft 3 is mounted in bearings 4. Upon said shaft 3 is centrally pivoted an oscillatory frame 5 carrying at one side of its pivot the motor 6. At the other side of said pivot a shaft 7 is mounted transversely of the frame 70 in bearings 8, said shaft being driven from the shaft 9 of the motor through the worm 10 and worm wheel 11. 12 is a pair of eccentrics fast upon the shaft 7 and engaging respectively in horizontally elongated openings 13 formed in a pair of oscillatory yoke members 14, which is pivoted terminally upon the end of the frame 5. The ends of the yoke members 14 adjacent the motor carry 80 a rod 17 upon which are swung pawls 18, 19, 20 and 21. The pawls 18 and 19 respectively engage ratchet wheels 22 and 23, mounted loosely upon the shaft 7, outside of the yoke members 14. The pawl 20 bears 85 upon a ring 24 concentrically secured to the ratchet wheel 22 and formed at one point of its periphery with a notch 25, which when registered with the pawl 20 permits the same to drop slightly from its normal position. 90 The pawl 21 is engageable with a short lateral extension 26 of the toothed rim of the ratchet wheel 23, when the rotative position of said ratchet wheel permits such engagement. The two pawls 19 and 20 are constrained to swing in unison by a bar 27 connecting their weighted lower ends. Upon one of its lateral faces the ratchet wheel 23 carries a cam 28 adapted to co-act with the stepped under face of an abutment arm 29, 95 integrally projecting from a standard 30 mounted fast upon the platform 2, said un-

100

der face having the upper and lower steps 31 and 32. Upon the end portions of the shaft 7 there are mounted fast gears 33, which, when the front end of the frame 5 is 5 upwardly rocked as shown in Fig. 3, are adapted to mesh with a pair of inverted rack-bars 34 secured at their forward ends to the drawer 1 by the brackets 35. The rear extremities of said rack-bars are attached 10 to the drawer extensions 1' by brackets 36 having integral depending extensions 37, the lower end portions of which extend toward each other as indicated at 38 to form keepers for gravity locking pawls 39 pivoted upon 15 the ends of the shaft 3. The free ends of said locking pawls are formed with heads to engage said keepers and the under faces of said heads are beveled as indicated at 40 so that they may ride upon the keepers to prevent 20 the latter offering any obstruction to the closing of the drawer. The ratchet wheels 22 and 23 are respectively engaged by detent pawls 41 mounted loosely on the shaft 15, which restrain said wheels against 25 rotation reverse to the step-by-step drive effected by the pawls 18 and 19.

As is shown in Fig. 1, the circuit 42 of the motor 6 includes the manually controlled switch 43, which may be remote from 30 said motor, and said circuit is further controlled by an automatic switch comprising the contact members 44 and 45, the former carried by the motor-supporting end of the rocker-frame 5, and the latter having its upper end pivoted at 46 upon a standard 47 mounted fast upon the base 2. Said standard further carries an adjusting screw 48 for positioning the member 45 to insure the proper engaging by gravity of said member 40 with the contact 44.

Considering now the operation of the described invention, normally the manually controlled switch 43 is open and the automatic switch 44, 45 is closed, the rocker frame 5 being maintained in the position shown in Fig. 2 by engagement of the cam 28 with the step 31 of the abutment arm 29. In case of an attempted hold-up the switch 43, which is so located as to be readily accessible, is closed. The motor 6, being thus energized, drives the shaft 7 through the worm 10 and worm wheel 11. Upon each revolution of the shaft 7 the yoke members 14 are oscillated by the eccentrics 12, and 50 the movement of the pawl 18 resulting from each oscillation is sufficient to advance the ratchet wheel 22 a distance equal to the circumferential extent of one of its teeth. Since under initial conditions, the lateral 55 extension 26 of the ratchet wheel 23 is engaged by the pawl 21 said wheel will similarly be subjected initially to a step-by-step drive in unison with the ratchet wheel 22. Just before this drive carries said lateral 60 extension clear of the pawl 21, the cam 28

will be shifted clear of the step 31, whereupon the weight of the motor will rock the frame 5 to the position shown in Fig. 3, meshing the rotating gears 33 with the racks 34. This effects a quick actuation of the drawer to its closed position, the drive connection being broken, when said position is reached, through the racks riding clear of the gears, as shown in Fig. 2. As the drawer approaches closed position, the keeper 38 lifts the pawl 39 through engagement with the beveled edge 40 thereof, said pawl dropping into locking engagement with the keeper, as shown in Fig. 3, after the latter has been shifted rearwardly from beneath the pawl. The drawer is now positively locked in closed position. To insure against the drawer being opened until enough time has elapsed to eliminate the danger, by reason of which the drawer was closed, a slow motion mechanism makes provision for releasing the drawer from the locking pawl. Thus a quite gradual step-by-step travel of the ratchet wheel 22 is effected by the pawl 18 due to oscillation of the yoke members 14. During the major portion of such travel the pawl 20 rides upon the ring 24, and by virtue of the connecting bar 27 holds the pawl 19 clear of the ratchet wheel 23. At one point, however, in each revolution of the ratchet wheel 22 and ring 24, the slot 25 in said ring registers with the pawl 20, allowing a sufficient swinging thereof to engage the connected pawl 19 with the ratchet-wheel 23. The length of the slot 25 is such as to permit such engagement to endure only during actuation of the ratchet wheel 23 through the circumferential extent of one tooth thereof. Thus while the drive of the ratchet wheel 22 is quite gradual, that of the ratchet wheel 23 is much more so since the latter shifts only the length of one tooth for each revolution of the former. As the ratchet wheel 23 completes a revolution, the cam 28 rides into engagement with the step 32 of the abutment arm 29 and rocks the frame 5 to the position shown in Fig. 4, in which the contact 44 is raised clear of the contact 45, breaking the circuit 42 and stopping the motor. Also as said frame assumes the position shown in Fig. 4, the arm 49, projecting from the frame 5, raises the pawl 39 clear of its keeper 38, permitting the drawer to be opened. The gears 33 being clear of the racks 34 in the described position of the frame 5, said elements will offer no resistance to opening of the drawer. As the drawer is initially opened after each locking operation a trip arm 50 pivotally mounted upon a bracket 51 carried by one of the racks 34 will engage a lug 52 on the rim portion of the ratchet wheel 23 rotating said wheel and its cam to the position shown in Fig. 2, in which the automatic switch 44, 45

is closed. The switch 43 having been opened, prior to opening of the drawer, no energization of the motor will occur, but the circuit will be closed to the motor so that 5 the latter will be energized whenever the switch 43 is again closed.

The time interval elapsing prior to unlocking of the drawer by the slow motion mechanism may be variously predetermined, 10 an hour ordinarily being ample time to eliminate a threatened danger of robbery. While the mechanism has been described as applied to a drawer, it is evident that the invention is broadly applicable to any 15 swinging or sliding receptacle for valuables.

What I claim is:

1. In a device of the character described, the combination with a drawer, of mechanism 20 for closing said drawer, a motor arranged to actuate said mechanism, controlling means for said motor, remote therefrom, a locking member for said drawer automatically engaging the same when closed, and a 25 slow-motion release mechanism for said member driven by said motor.

2. In a device of the character described, the combination with a receptacle for valuables, of an electric motor for closing said 30 receptacle, a switch remote from said motor controlling the same, means effective upon closing of the receptacle for automatically locking the same, a slow-motion release mechanism for the locking means driven by 35 said motor, and a switch controlling the motor automatically opened by said release mechanism upon release of the locking means.

3. In a device of the character described, 40 the combination with a receptacle for valuables, of an electric motor for closing said receptacle, a manually operable control switch for said motor remote therefrom, means effective upon closing said receptacle 45 for locking the same, a second motor control switch in series with the first-mentioned switch and arranged adjacent the motor, and means operable by the motor for opening said adjacent switch subsequent to closing of 50 said receptacle by the motor.

4. In a device of the character described, the combination with a drawer, of a rack carried thereby, extending in the direction 55 of travel of the drawer, a motor stationary with respect to said rack, a gear adapted to mesh with the rack, a slow-motion drive from said gear to said rack, means remote from said motor for controlling the same, and means effective upon closing the drawer 60 for automatically locking the same.

5. In a device of the character described, the combination with a drawer, of a mechanism 65 for closing said drawer, a motor for driving said mechanism, means normally breaking the drive connection from said

mechanism to the drawer to provide for normal operation of the drawer independently of said mechanism, means remote from the motor for controlling the same, means effective upon closing of the drawer for locking 70 the same, and means operable by the motor for establishing the drive connection from said mechanism to the drawer, upon energization of the motor.

6. In a device of the character described, the combination with a receptacle for valuables, of a motor for closing said receptacle, a pivotal support for said motor, means remote from the motor for controlling the same, means effective upon closing said receptacle for automatically locking the same, means effecting an automatic control of the motor through movement of the pivotal support for the same, a slow-motion mechanism driven by the motor, and means operable by 80 said slow-motion mechanism after a predetermined time interval to de-energize the motor through actuation of said pivotal support.

7. In a device of the character described, the combination with a receptacle for valuables, of an electric motor for closing said receptacle, an intermediately pivoted frame supporting said motor substantially at one side of its pivot, a slow-motion mechanism driven by the motor and mounted upon said frame at the other side of its pivot, a switch remote from said motor controlling the same, another control switch for the motor urged to closed position by said frame under weight of the motor, means effective upon closing of the receptacle for automatically locking the same, and means actuatable by said slow motion mechanism for rocking said frame counter to the weight of the motor, after a predetermined operation of the motor for opening the adjacent control switch.

8. In a device of the character described, the combination with a receptacle for valuables, of an electric motor for closing said receptacle, a switch remote from said motor controlling the same, a pivotal frame supporting the motor, an automatic control switch for said motor, controlled by rocking 110 of said frame, a normally open drive connection for closing the receptacle by the motor controlled by rocking of said frame, mechanism driven by the motor upon initial energization thereof, for rocking the frame sufficiently to close the drive connection for closing the receptacle, means effective upon closing of the receptacle for locking the same, and a slow-motion mechanism driven by the motor effective to further rock said frame after a predetermined time interval 115 to open said automatic control switch.

9. In a device of the character described, the combination with a receptacle for valuables, of an electric motor for closing said 120 receptacle, a switch remote from said motor

controlling the same, means effective upon closing of the receptacle for automatically locking the same, a slow-motion release mechanism for the locking means driven by said motor, a switch controlling the motor automatically opened by said release mechanism upon release of the locking means, and

means carried by the drawer effecting closing of the last mentioned switch as the drawer is opened.

10

In testimony whereof I sign this specification.

EDWIN M. CLARK.
